METHOD OF FORMING PLOW DISKS

Roy C. Ingersoll, Winnetka, Ill., assignor to Borg-Warner Corporation, Chicago, Ill., a corporation of Illinois

Application October 25, 1939, Serial No. 301,099

10 Claims. (Cl. 29—14)

This invention relates to disks, and particularly to a method of forming plow, harrow and other tapered agricultural disks. This application is a continuation in part of my co-pending application Serial No. 159,089, filed August 14, 1937.

The usual plow disk is comprised of a steel disk which has been cambered or dished to a substantially frusto-spheroidal shape. The edge of the disk is beveled to present a sharp cutting edge to the soil, and the central region is provided with a suitable aperture for mounting the disk upon the implement with which it is to be used.

The practice generally employed for forming plow disks is to start with a flat blank, heat the blank to forging temperature, roll a bevel on the edge region, and then drop forge the disk between suitable dies to a cambered shape. In the forging operation, however, the movement of the metal is uncontrolled. Obviously, as the contour of the disk is changed from planar to spherical, the metal must be upset in order to allow for the decreased diameter which results. Upsetting, however, requires a considerable amount of force in the plane of the metal and in view of the thinness of the metal, together with its softness at forging temperatures, the metal tends to buckle and form wrinkles rather than upset.

It has been the practice to camber the disk by means of several light blows with the drop hammer, rather than with a single heavy blow, to reduce the amount of buckling, and to strike the disk sharply after it has been substantially completely cambered in order to remove wrinkles. This practice has never been completely satisfactory, partly because of the increased time required to form the camber, and partly because the wrinkles were not completely eradicated by the final sharp blows. To function properly as a plow the disk must be perfectly smooth, otherwise it will not scour properly. The resulting disk, therefore, had to be ground to remove the last vestiges of the wrinkles.

The object of this invention is to provide an improved method for forming cambered disks in the exercise of which the metal of the disk is completely under control during the entire forming operation, thereby eliminating wrinkles in the finished disk.

Another object of this invention is to provide a method for forming cambered disks which is more economical and less time-consuming than those heretofore used.

These and other objects of this invention will become apparent from the following description

when taken together with the accompanying drawings forming part thereof, in which:

Fig. 1 is a beveled flat disk from which the plow disk is made;

5 Fig. 2 is an elevation in section of the drawing dies used in the method of forming the camber in the disk of Fig. 1;

Fig. 3 is an enlarged fragment of the dies of Fig. 2 showing the initial stage of the operation 10 of the dies;

Fig. 4 is an enlarged fragment in section of the dies showing an intermediate stage; and

Fig. 5 is an enlarged fragment in section showing the final stage of the operation of the die.

15 In its preferred form, this invention comprises the steps of heating a steel disk to forging temperature, rolling a bevel on one surface of the disk, gripping the disk over the beveled region thereof, simultaneously drawing the disk over a convex die, and, finally, compressing the entire disk between the dies. I am aware that it is old to form sheet metal to various shapes by means of a drawing operation. The ordinary drawing operation, however, if applied to a plow disk would 20 not be satisfactory for the reason that it would result in a disk which is deeply scarred with die marks. These die marks could, of course, be eliminated by starting with a very large disk and then trimming off the portion which is marked. Such a procedure, however, would be too costly 25 to be commercially feasible. The problem has been to camber a disk by means of dies in a manner which would not require any subsequent trimming operation, which would not result in die marks and which nevertheless, would eliminate 30 wrinkles.

I have discovered that a satisfactory cambered plow disk may be obtained by gripping the beveled portion of the disk with a draw ring, the operative surface of which is an extension of the surface of the central portion of the die, and by permitting the upper die to slide over the beveled portion as the draw ring moves with the die. By so gripping the disk, the material will bend at 40 the outer ends rather than take an impression from either die, and, in addition, will be sliding over the surfaces of the disk continuously, thereby preventing a concentration of force at any one point.

45 Referring now to the drawings for a detailed description of the invention, the flat blank from which the plow disk is formed is shown in Fig. 1. The blank 10 is heated to forging temperature and then is placed between suitable rolls to form a bevel 11 on one surface thereof.

The heated and beveled disk 10 has an aperture 12 formed therein, preferably prior to the rolling operation and simultaneously with the blanking operation. The disk is placed upon a die 13 having a centering pin 14 which passes through aperture 12. Disk 10 rests upon a hardened insert 15 and also upon the upper corner 16 of draw ring 17. Insert 15 has formed therein a shoulder 18 which connects a flat surface 19 at the central portion with a convex surface 20 in the edge region of the insert.

The upper surface 21 of die 13 is an extension of surface 20. The upper surface 22 of draw ring 17 is an extension of surface 21 of die 13 so that when draw ring 17 is at the bottom of its stroke, surfaces 20, 21 and 22 form continuations of one another.

The draw ring 17 rests upon pins 23, which are spaced circumferentially about die 13 and are urged upwardly by means of springs 24, compressed air, or the like.

Upper die 25 has a central insert 26 which cooperates with insert 15 to form the central region of disk 10. Upper die 25 extends over both lower die 13 and draw ring 17. Its concave surface 27 is adapted to form the upper surface of disk 10.

Referring now to Figs. 3, 4 and 5, the method of cambering disk 10 is as follows:

It will be noted in Fig. 3 that corner 16 of draw ring 17 contacts the lower surface of disk 10 just below the point where bevel 11 joins the remainder of the upper surface of disk 10. It will also be noted that the corner 28 formed by the concave surface 27 of upper die 25 and the unformed flat surface 29 contacts disk 10 on the beveled portion thereof and a slight distance inward from the edge of the disk. The first step in the cambering operation, therefore, is to grip disk 10 between draw ring 17 and upper die 28 at the beveled region of the disc. It will be noted that the gripping action is not a compressing action, but rather a bending action.

As the upper die descends, it soon exerts enough force to overcome the upward thrust of springs 24 upon pins 23 and draw ring 17 then commences to move downward with the upper die. Before it begins its descent, however, disk 10 will be bent over corner 16 and as draw ring 17 descends, the metal of disk 10 will be drawn downward and radially inward over corner 16 as shown in Fig. 4. Simultaneously corner 28 of upper die 25 slides radially outwardly along bevel 11, contacting progressively thinner and consequently more easily bent sections of the disk as it slides. This results in a continuous flexure over corner 16, which is necessary to provide the gripping action for drawing the disk downwardly and at the same time exerting enough tension on the metal as it upsets to prevent the formation of wrinkles.

Near the bottom of the stroke, where the bent surface of the disk is substantially parallel with the surface of the lower die and draw ring, the gripping action is no longer confined to corners 16 and 28, but takes place along the upper surface of draw ring 17 and the lower edge region of surface 27 of upper die 25, which region has been shaped to accommodate the bevel. From this point on, the shoulder 18 in insert 15 commences to form disk 10, and in so doing, still further adds to the forces tending to slide disk 10 over the draw ring and the surface of upper die 25. At the bottom of the stroke, draw ring 17 rests upon base plate 30 of the press and becomes a part of

lower die 13. The disk is then compressed between the dies to give it its final form. It will be noted that at the bottom of the stroke edge 28 of upper die 25 coincides with the edge of disk 10, and therefore, will form no marks thereon.

The foregoing method results in a plow disk which is perfectly cambered, and which is neither wrinkled nor deeply marked by dies. The disk requires no subsequent trimming operation, since it was formed in its entirety between the dies. The reason for the success of this method where the ordinary draw ring method fails, is in the location of the draw ring with respect to the disk. Thus, if the draw ring and lower die were parted at a distance radially inward from the position shown, a satisfactory result could not be obtained. The portion between the draw ring and the center of the disk might be properly formed, but the force required to do so would be such that the draw ring would bite into the under surface of the disk. On the other hand, if draw ring 17 and lower die 13 were parted at a distance radially outward from the one shown, the force upon the bevel would be too great for the thickness of metal thereat for one thing, and in addition, the upper die would slide off the bevel and thereby destroy the gripping action which is so necessary for the drawing operation.

Draw ring 17 also acts as an ejector for the disk and for this reason a portion of the disk must remain over draw ring 17 at the end of the stroke.

It is understood that the foregoing description is merely illustrative of the preferred embodiment of my method, and that the scope of this invention, therefore, is not to be limited thereto, but is to be determined by the appended claims.

I claim:

1. The steps in the method of making agricultural implement disks which comprise forming a bevel on one surface of a disk, cambering the disk by drawing the disk over a convex die, and simultaneously gripping opposite sides of the disk at the beveled region with line contact to prevent the formation of wrinkles in the disk.

2. The steps in the method of making plow disks which comprise forming a bevel on one surface of a flat disk, cambering the disk by drawing the disk over a convex die, and gripping opposite sides of the disk with line contact during the drawing operation to prevent the formation of wrinkles in the disk, said gripping action being limited to substantially the beveled region of the disk.

3. The steps in the method of making plow disks which comprise forming a bevel on one surface of a flat disk, cambering the disk by drawing the disk over a convex die, and gripping opposite sides of the disk with line contact over the beveled region during the drawing operation, said gripping action being just sufficient to prevent the formation of wrinkles in the disk but being insufficient to form an appreciable die mark in the disk.

4. The steps in the method of forming plow disks which comprise heating a flat disk to forging temperature, forming a bevel on one surface, cambering the disk by drawing said disk while hot over a convex die, gripping opposite sides of the beveled region with line contact during the drawing operation to prevent the formation of wrinkles in the disk, and compressing the beveled region between dies to shape said beveled region.

5. The steps in the method of forming plow disks as described in claim 4, said gripping action being sufficient to prevent the formation of

wrinkles, but being insufficient to cause appreciable marks in the disk.

6. The steps in the method of making plow disks which comprise forming a bevel on one surface of a disk, cambering the disk by drawing the disk over a convex die, gripping opposite sides of the beveled region with line contact during the drawing operation with a force sufficient to prevent the formation of wrinkles in the region between the inner edge of the bevel and the center but insufficient to mark the disk, and compressing the beveled region between dies to shape said region.

7. The steps in the method of making plow disks which comprise heating a disk to forging temperature, rolling a bevel on one surface of the disk, cambering the disk by drawing the disk over a convex die, gripping opposite sides of the beveled region with line contact during the drawing operation with a force sufficient to prevent the formation of wrinkles in the region between the inner edge of the bevel and the center, but insufficient to indent the surface of the disk, and compressing the entire disk including the beveled region, between dies to shape the disk.

8. The steps in the method of making plow

disks which comprise forming a bevel on one surface of a disk, cambering the disk by drawing the disk over a convex die, and simultaneously gripping the disk at the beveled region with a bending action which imposes a sufficient radial force on the disk to prevent the formation of wrinkles therein, but which is insufficient to form appreciable die-marks.

9. The steps in the method of making plow disks which comprise forming a bevel on one surface of a disk, cambering the disk by drawing the disk over a convex die, and simultaneously progressively bending the beveled region radially outward over a draw ring, the bending action being insufficient to form appreciable die-marks, but being sufficient to prevent the formation of wrinkles in the disk.

10. The steps in the method of making plow disks in accordance with claim 9, and finally compressing the entire disk between dies to form a shoulder in the disk, said shoulder-forming step causing a radially inward movement of the metal over the dies to prevent a concentration of force over a small area whereby to prevent the formation of die-marks in the final step of the method.

ROY C. INGERSOLL.
